AUTOMATIC TELEPHONE SYSTEM

Bernard D. Willis, Oak Park, Ill., assignor, by
mesne assignments, to Associated Electric Lab-
oratories, Inc., Chicago, Ill., a corporation of
Delaware

Application October 7, 1935, Serial No. 43,903

17 Claims. (Cl. 179—18)

The present invention relates in general to automatic telephone systems, and more especially to systems of the type which employ separate setting and speaking routes, commonly known as by-pass systems. The object of the invention is to provide a new and improved system of this character which is better adapted to present commercial requirements than those heretofore available.

10 The invention will be described hereinafter with reference to the accompanying drawings, comprising Figs. 1, 2, and 3, which show by means of the usual circuit diagrams sufficient of the equipment involved to enable the invention to be explained and understood.

Referring to the drawings, Fig. 1 shows at the left a subscriber's station A, having a line extending to the exchange and there equipped with the usual line and cut-off relays.

20 The line of station A may be one of a group of two-hundred lines which are accessible to a group of connectors and also to a group of finders, preferably of the Strowger type. Fig. 1 indicates one finder of the group, denoted by the reference character F, and also a distributor D which is common to the group. The finder and distributor may have any well known circuit arrangement and hence the detailed circuits are not shown. The Saunders Patent No. 1,851,132, 25 granted March 29, 1932, shows a finder system that may be used.

Associated with the finder F is a trunk circuit TC, which comprises the relays shown and a step-by-step sender SD.

30 The trunk circuit TC is accessible to a number of so-called confluence switches such as CS, which are also preferably of the Strowger type. The switch CS has access to two hundred trunk circuits such as TC. Assuming that sixteen trunk circuits, or finders such as F, are required for each group of subscribers' lines, the arrangement shown comprising a single group of confluence switches gives a capacity of twelve groups of subscribers' lines, or 2400 lines, with eight trunks 35 remaining which can be allotted to additional finders in busy groups if required.

Fig. 2 shows a connector switch C, having access to two-hundred subscribers' lines one of which is the line of station B. The connector C may be directly paired with the confluence switches CS, as shown in the drawings. There are, of course, as many groups of connectors as there are groups of subscribers' lines, and each connector has an associated confluence switch.

40 Considering now the switches in the setting

route, shown in Fig. 3, these switches comprise trunk finders such as F', arranged in several groups, first selectors such as S1 and second selectors such as S2. The selectors may be of the Strowger type, preferably. The trunk finders such as F' may be rotary single motion finders, and if each finder has access to fifty trunks, as is usual in the case of rotary finders, there would be four groups required to take care of two-hundred trunk circuits TC. 10

The equipment involved having been described, the operation of the system will be explained. For this purpose it will be assumed that the subscriber at station A desires to set up a connection to the line of station B. Upon the removal 15 of the receiver at station A a bridge is closed across line conductors 2 and 3 and the line relay 4 is energized. On energization, the line relay connects the cut-off relay 5 to multiple test contacts such as 8 in the finder banks and grounds 20 the start wire 13. Through the medium of the distributor D an idle finder is now started up in search of the calling line. Assuming the finder F is used, the switch is first operated in its vertical motion under control of vertical test wiper 14, and then in its rotary motion under the control of its test wiper 11, and is stopped when the latter wiper reaches test contact 8 of the calling line. At this point the finder test relay energizes in series with the cut-off relay 5, the latter 30 relay energizing also. On energizing, relay 5 locks itself to the test lead coming from the finder and also connects this test lead to the test lead 6 extending to the connector banks, where the calling line is made busy. Relay 5 also disconnects the line relay 4, permitting it to deenergize. 35

The calling line conductors 2 and 3 are thus extended through by way of bank contacts 7 and 9, and finder wipers 10 and 12, to the line relay 16 in the trunk circuit TC, where the said relay 16 is accordingly energized. On energizing, line relay 16 grounds the conductor 25 at 27 to provide a holding circuit for the finder F and cut-off relay 5, connects the cut-off relay 17 to the 40 test lead 33 at 28, and at 29 grounds the finder start lead 30.

As a result of the grounding of the start lead 30, the start relay 101 in the trunk finder F' pulls up, prepares the test circuit at 109, closes 45 a circuit for the lower polarizing winding of test relay 102 at the same point, and closes a circuit for stepping magnet 104 at 110. On energizing, the stepping magnet 104 closes a circuit for stepping relay 103, which energizes and breaks 50

55

the circuit of magnet 104, the latter falling back and advancing the finder wipers 105—108 one step. This interaction of magnet 104 and relay 103 continues, and the finder wipers are advanced step by step, until the test wiper 107 engages the test contact 117, where it finds a battery potential on conductor 33. As a result the stepping relay 103 is held energized, and relays 102 and 17 are energized in series over a test circuit which extends from ground at 109 by way of 102, 103, 107, 117, 33, contacts controlled by 39, 28, and 17 to battery.

Considering first the effect of energizing relay 17, this relay locks itself at 36, closes the finder holding circuit at 35, opens the start circuit at 37, and at its outer contacts disconnects the line relay 16, which falls back. By this time, however, the lead 33 has direct ground on it, as will subsequently appear, and the finder holding circuit is maintained over 33, contacts controlled by 39, 35, and 25.

At the finder F', the holding up of relay 103 prevents the possibility of reclosing the circuit of magnet 104 and insures a positive stopping of the finder. Test relay 102, on energizing, breaks the circuit of magnet 104 at 115, transfers the finder start circuit at 116, and closes its contacts 113 and 114. The effect of closing these two contacts is to short circuit the upper windings of relays 102 and 103 and to connect the test lead 33 to test lead 123. Since the upper windings of relays 102 and 103 are short-circuited the test lead 33 will be grounded at 109 until the slow-acting start relay 101 falls back. Relay 102 is held energized over its lower or polarizing winding, which is able to maintain the relay after it is once operated. Relay 103 falls back.

The test relay 102 also extends the line conductors 31 and 32 by way of wipers 105 and 106 and contacts 111 and 112 to the windings of the line relay 124 of the first selector S1. The line relay accordingly energizes and closes a circuit for the slow-acting release relay 125, which energizes in turn and places ground on the test lead 123, thereby completing a holding circuit including conductors 123, 33 and 25. The release relay grounds this circuit before relay 101 has had time to fall back.

Due to ground on the conductor 123 the slow-acting changeover relay 126 also energizes at this time, and connects the dial tone circuit to the lower winding of line relay 124 in place of direct ground. Upon hearing the tone in his receiver the calling subscriber knows that he can proceed to dial the number of the desired line.

The general operation of selectors such as S1 and S2 is well known and hence may be explained rather briefly. Responsive to the dialling of the first digit the line relay 124 is deenergized a number of times and sends a series of impulses to the vertical magnet 128. The magnet 128 responds to these impulses and steps up the shaft carrying wipers 131—134 until they stand opposite the level corresponding to the digit dialled. At the first vertical step the off-normal contacts ON are shifted, one result being to open the initial energizing circuit of relay 126, but this relay is maintained during the vertical operation by its lower winding, which is in parallel with the vertical magnet 128.

At the end of the first digit the line relay 124 comes to rest in energized position and relay 126 falls back, closing a circuit for rotary magnet 129. The rotary magnet 129 therefore energizes, and since it interrupts its own circuit, it

operates in buzzer fashion to rotate the wipers 131—134 in search of an idle trunk line. When an idle trunk line is reached, assumed in this case to be the trunk line extending to the second selector S2, the test wiper 134 will find a battery potential on test contact 138 and the electro-polarized test relay 127 will energize in series with the changeover relay 152 of the second selector. On energizing, relay 127 breaks the circuit of the rotary magnet to stop the rotary movement. Relay 127 also extends the holding circuit forward by connecting conductor 123 to the test wiper 134. This short circuits the upper winding of relay 127 but the relay holds up by means of its lower polarizing winding. In addition, relay 127 extends conductor 120 forward to wiper 133, and closes a bridge across wipers 131 and 132.

Upon the seizure of the second selector S2, as described in the foregoing, the relay 152 energizes as previously mentioned. The line relay 150 energizes also, due to the bridge across wipers 131 and 132 at the first selector S1. The line relay closes a circuit for the slow-acting relay 151. This is the usual release relay, but in the present case it does not ground the holding circuit because ground is fed forward from the first selector S1.

The calling subscriber may now dial the second digit of the called number, causing a second series of deenergizations of the line relay 124. Each time the line relay falls back it breaks the bridge across wipers 131 and 132 at contact 139, and thus the digit is repeated on to the second selector S2 by producing a series of interruptions in the circuit of line relay 150. Under control of line relay 150 the selector S2 is operated and the wipers 161—164 are first stepped up vertically and are then rotated in search of a trunk line leading to an idle connector. Assuming that the connector C, Fig. 2, is the first connector found idle, when test wiper 164 reaches test contact 168 it finds a battery potential and the test relay 153 energizes in series with relay 207 of the connector C. On energizing, relay 153 opens the rotary magnet circuit, extends the holding circuit forward by connecting it to test wiper 164, and locks itself to the holding circuit. Relay 153 also disconnects the line relay 150 and extends the repeating loop forward to wipers 161 and 162.

Upon the seizure of the connector C, therefore, the line relay 201 energizes, as well as relay 207, its lower winding getting its ground connection from the now grounded holding conductor 216, and closes a circuit for the release relay 202. On energizing, relay 202 prepares the vertical magnet circuit at 225 and at 222 it connects another ground to the holding conductor 216.

The calling subscriber may now dial the third digit of the number, which is repeated by the line relay 124 of the selector S1 to the line relay 201 of connector C. Line relay 201 accordingly deenergizes a plurality of times and sends a series of impulses to the vertical magnet 211 over a circuit extending from ground at 221 by way of 225, 276, 247, 239, and winding of 211 to battery. The vertical magnet 211 responds to the series of impulses and steps up the shaft carrying the set of wipers 282—284 and the set of wipers 285—287. The connector C has a capacity of 200 lines and has two sets of wipers. The slow-acting relay 205 is energized in parallel with the vertical magnet 211 and remains operated during the series of impulses. Upon the first vertical step of the switch the off-normal springs are shifted, and

the initial energizing circuit of relay 207 is broken. The relay is held up, however, over a circuit extending from ground by way of 224, 261, 232, 238, and winding of 207 to battery.

- 5 At the end of the vertical operation, the slow-acting relay 205 deenergizes, followed by the de-energization of relay 207. The latter relay transfers the impulse circuit from vertical magnet 211 to rotary magnet 212 at 239.
- 10 The calling subscriber may now dial the fourth digit of the called number, and the digit is repeated as before to the line relay 201. This relay now sends a series of impulses to the rotary magnet 212 over the circuit—ground at 221, 225, 216, 15 247, 239, 262, 271, and 212 to battery. The rotary magnet responds and rotates the two wiper sets of the connector in on the bank levels selected by the vertical movement, the upper set of wipers 282—284 engaging the contacts 290—292 of the 20 line of station B. Relay 205 energizes in parallel with the rotary magnet, and closes a circuit for relay 210, said circuit extending from ground at 224 by way of 261, 232, 238, resistance 288, and upper winding of 210 to battery. Relay 210 is 25 a two-step relay and only closes its contacts 270 and 277 when energized over the above circuit. At the end of the rotary movement relay 205 falls back and closes a circuit for fully operating relay 210, the circuit extending from ground at 224 by 30 way of 261, contacts controlled by 232, 270, and upper winding of relay 210 to battery. Relay 210 now operates fully, locks itself at 265, and at 271 shifts the impulse circuit from the rotary magnet 212 to the relay 209. It will be noted 35 also that relay 210 disconnects the wiper set 282—284 and connects up wiper set 285—287.

The calling subscriber may now dial the final digit of the called number. The final digit is either the digit one or the digit two, which respectively select the wiper sets 285—287 and 40 282—284. In the present case the called line is reached by way of wiper set 282—284 and hence the final digit is two. When the line relay 201 responds, the first impulse is transmitted to the 45 lower winding of relay 209, the impulse circuit having been transferred from the rotary magnet by relay 210. Relay 209 is also a two-step relay and only closes its contact 269 responsive to the impulse. When the impulse is over, the relay 50 209 operates all the way, due to energization of both windings in series, and at 262 transfers the impulse circuit to the lower winding of relay 210. The second impulse now comes in and causes the deenergization of relay 210, due to the fact that 55 the two windings of the relay oppose each other. Contacts 270 and 272 break at substantially the same time. With relay 210 deenergized the wiper set 282—284 is again connected. It will be evident that if the last digit had been one instead 60 of two, relay 210 would have remained energized, and wiper set 285—287 would have remained connected.

65 Relay 209, which is always energized on the last digit, disconnects ground from contact group 232 at 261, and closes a point in the test circuit at 249. Relay 205 is energized during the dialling of the last digit, and as soon as relay 209 operates, the test circuit is completed first to test wiper 286 and then to test wiper 283, the latter test wiper 70 being substituted for the former by the falling back of relay 210 on the second impulse. The test circuit may be traced from test wiper 283 by way of 264, 249, upper winding of relay 208, 231, resistance 289, and winding of test relay 203 to battery. If the line of station B is busy there will 75

be a ground potential on test contact 291 and relay 203 will be energized, operating only part way, however, sufficient to close contact 275. Resistance 289 is high enough to prevent the energization of relay 208 and to prevent the full operation of relay 203. At the end of the final digit relay 205 falls back, the resistance 289 in the test circuit is cut out, and a branch circuit 251 is substituted for the resistance. This lowers the resistance of the test circuit sufficient to operate 10 relays 208 and 283. The former relay is slow to operate, however, and relay 203 operates and locks itself at 274, breaking the test circuit at the same time, before relay 208 can get started. In energized position, relay 203 opens the impulse circuit 15 at 276, and connects a source of busy signalling current to the talking conductor 215 at 273. As will appear subsequently the calling line has already or shortly will be extended through to the connector C. In either case he will hear the busy 20 signal and will understand that the called line is engaged.

Assuming now that the called line is idle, when the test circuit is established as described in the foregoing, the test relay 203 will not be energized, 25 due to absence of ground potential at test contact 291. When relay 205 falls back therefore a circuit will be closed which extends from ground at 223 by way of 275, 251, upper winding of 208, 249, 254, 283, 291, and winding of cut-off relay 293 30 to battery. Relays 208 and 293 energize in series over the above circuit and the latter relay disconnects the line relay 294. Relay 208 energizes over the series circuit sufficient to close its contact 245, and then operates all the way due to energization 35 of its lower winding. In energized position relay 208 breaks the impulse circuit at 247 and grounds the test wiper 283 at 244. Relay 208 also closes the ringing circuit at 241 and 248, and at 242 connects a source of ring-back tone to the talking 40 circuit.

Leaving the connector C in this condition, with the bell at station B ringing, attention may be directed to the operation of the confluence switch CS, which begins at the moment the connector C is stepped off normal responsive to the third digit 45 dialled. When the off normal springs are shifted on the first vertical step of the connector a connection is established between conductors 171 and 219, completing a circuit for relay 19 of the trunk 50 circuit TC, which extends from the grounded holding circuit including conductor 33 by way of 38, winding of 19, 34, 108, 120, 133, 137, 163, 167, 171, off-normal contact, 219, side-switch SS in first position, and winding of vertical magnet 60 55 to battery. Relay 19 is energized over the above circuit, magnet 60 being unaffected due to the relatively high resistance of relay 19. On energizing, relay 19 locks itself at 41 and cuts off its original energizing circuit, which is connected to contact spring 23 of the sender SD at 42. Relay 19 also closes a circuit for the stepping magnet 20 of the sender at 40.

The stepping magnet 20 interrupts its own circuit and accordingly begins to operate in the manner of a buzzer to rotate the shaft carrying the cams 21 and 22. On the first step cam 21 shifts the spring 46, thereby substituting a local ground connection for the circuit through contact 49 of relay 19. This operation insures that the 60 sender magnet 20 will drive the cams through a complete revolution and return them to normal, even if the calling subscriber should hang up.

As the cam 22 rotates, the spring 23 first encounters the projections 47, which force spring 75

23 twice into engagement with ground spring 44 and thus send two impulses to the vertical magnet 60 of switch CS over the circuit: ground, 44, 23, 42, 34, 168, 120, 133, 137, 167, 171, 219, SS, and 5 winding of 60 to battery. The vertical magnet 60 responds to these impulses and raises the shaft carrying the two wiper sets 53-55 and 83-85 two steps.

Cam 22 continues its rotation and eventually 10 the spring 23 drops into the notch 48, which causes it to momentarily engage spring 45. This operation connects a source of alternating current A. C. to the impulse circuit and thus transmits an impulse of alternating current. The current 15 is of high enough frequency and the circuit includes sufficient resistance so that magnet 60 is not affected, but the alternating current relay 58 responds to the impulse and operates the private magnet 62. The operation and release of 20 magnet 62 advances the wiper of side switch SS one step by means of the usual escapement.

Further rotation of cam 22 causes projection 25 49 to engage spring 23, and another ground impulse is transmitted, causing the operation of the 25 rotary magnet 61. Magnet 61 rotates the switch shaft one step and brings the wiper set 53-55 into engagement with bank contacts 50-52.

As cam 22 continues its rotation, the spring 23 falls successively into the notches 71, sending out 30 two alternating current impulses. These impulses cause two operations of relay 58 and private magnet 62, and the wiper of side switch SS is advanced two steps so as to connect with relay 57. Further movement of the cam now sends a 35 single final ground impulse by means of projection 72, which operates relay 57. Relay 57 is a connecting relay and extends the trunk conductors 215, 216, and 218 back to the wipers 53, 54, and 55. Relay 57 also locks itself to the holding 40 conductor 216 and disconnects conductor 216 from conductor 172.

The cams 21 and 22 reach their normal position shortly after the last impulse is transmitted and spring 46 falls into the notch in cam 21, thus 45 stopping the operation of the stepping magnet 20. In the meantime relay 19 has fallen back, so that the sender is not restarted. When relay 57 energizes responsive to the last impulse a circuit is completed for relay 18, said circuit extending from the grounded holding conductor 216, by way of contacts of 57, 54, 51, and winding of 18 to battery. Relay 18 energizes and completes the final holding circuit at 39, disconnecting conductor 33 at the same point. Relay 18 also 55 unlocks relay 19 at 38, and at its upper and lower contacts disconnects the conductors 31 and 32.

The latter operation initiates the release of the switches in Fig. 2. The line relay 124 falls back followed by relay 125. Thus a circuit is closed 60 for the release magnet 130 and the selector S1 is restored to normal. The deenergization of relay 125 also removes ground from the holding circuit and relay 102 of finder F' falls back, also relay 153 of selector S2. Relay 153 closes a circuit for release magnet 156 and the selector S2 is restored to normal.

It will be seen now that the calling line has been extended to the connector C by means of the confluence switch CS and that the switches 70 F1, S1, and S2, Fig. 3, have been eliminated. The connection is held up by ground applied to holding conductor 216 by relay 202 of the connector C.

When the called subscriber at station B answers, the ring-cut-off relay 206 energizes and

locks itself at 234. Relay 206 also closes a circuit for relay 207 by way of 243 and 233, and relay 207 energizes. By the operation of relay 207 the ringing circuit is broken and the talking circuit is extended back at contacts 236 and 240, 5 and the ring-back tone circuit is opened at 231. The back bridge relay 204 now energizes over the called line. At 229 relay 204 opens the release magnet circuit, and at 228 it gives its lower winding another ground connection by way of 235 10 and 246. In addition, relay 204 disconnects the line relay 201 from conductors 215 and 218 at 227 and 230 and substitutes for the line relay the battery feed relay 200. This completes the talking circuit, and also reverses the direction of 15 current flow in the calling line. Relay 200 energizes and at 220 closes a local circuit for line relay 201 in order to reoperate the same and hold it and the release relay 202 energized.

The calling and called subscribers may now 20 converse as desired, transmitter current being supplied through the windings of relays 200 and 204. These relays have ballast resistances 296 and 297 in series with them in order to maintain a substantially constant current value 25 regardless of the length of the subscribers' lines. When the subscribers are through talking they will hang up their receivers. When the receiver is replaced at station A the battery feed relay 200 falls back, allowing the line relay 201 to fall 30 back also. The release relay 202 then restores after an instant and removes ground from the holding conductor 216. This allows relays 57, 18, and 17 to deenergize. The cut-off relay 5 also restores, and at the same time the finder F is 35 restored in the usual manner. At the connector C the release of the switch depends on whether the called party has hung up or not. When relay 202 falls back it opens the local holding circuit at 224 and closes a point in the release circuit at 226. If the receiver is still off at station 40 B the back bridge relay 204 will stay energized and hold open the release circuit at 229. When the receiver is replaced at station B, relay 204 deenergizes, removes ground from the locking 45 circuits of relays 206 and 208, permitting these relays to deenergize to free the called line, and closes the release circuit at 229. Release magnet 213 accordingly operates to restore the connector C. The release magnet 63 of switch CS is also 50 operated, over conductor 217, and restores the switch CS and its side switch SS to normal. All the apparatus is thus placed in condition for use in another call.

Some additional remarks may now be inserted 55 with a view to a fuller explanation of certain features than appeared advisable in the course of the regular circuit explanation. To begin with, it will be understood that the sender SD is individual to the trunk circuit TC. Each trunk circuit such as TC has a sender SD and also has a code number allotted to it which corresponds to the position of the trunk circuit in the banks of the confluence switches and which the associated sender is arranged to send out whenever it is operated. 60 Thus the code assigned to the trunk TC is 212, the sender SD always sends out this number, and any confluence switch operated in accordance therewith will connect with the particular trunk circuit TC and no other. If there are two-hundred 65 trunks such as TC there will be two hundred different code numbers assigned. The cams 22 of the senders are cut in accordance with the different code numbers. There would be for instance, one-hundred cams arranged to send numbers 112 70 75

to 002, one-hundred numbers in all, each cam having two notches 71, providing for one hundred numbers ending in the digit two. There would also be one-hundred similar cams, except for having only one notch 71, providing for sending one-hundred numbers ending in the digit one. The cams in the two groups serve to operate switches such as CS the same, except that those sending out code numbers ending in the digit two operate 5 relays such as 57, while those sending out code numbers having the final digit 1 operate relays such as 56. This brings into play both wiper sets of switches such as CS and gives the switches access to two-hundred trunk circuits such as TC. 10 As stated earlier in the specification the capacity of a system having 200 trunk circuits TC is about 2400 lines. The capacity can obviously be increased by adding additional wiper sets to the confluence switches CS. For instance the switch 15 CS could be provided with a third set of wipers and another relay similar to relays 56 and 57. This would provide for another hundred trunk circuits TC. The cams 22 of the senders SD associated with the third hundred trunk circuits 20 would be the same as the others except that they would each have three notches such as 71.

There is a limit to the number of wiper sets that can be economically added to the confluence switches and consequently for very large systems 25 a different plan would be followed. An obvious arrangement is to divide the confluence switches into groups and insert group selectors between the connectors and the confluence switches. In this arrangement each connector would be paired 30 with a group selector, and each group selector would have access to confluence switches in each group. The senders SD would also be arranged so as to send out four digits instead of three, the first digit serving to operate a group selector. 35

40 In describing the operation of the system it was assumed that the connector C was completely operated by series of impulses repeated by the line relay 124 of selector S1. In actual practice, however, it is more or less a matter of chance that the connector is fully operated in this manner. The operation of the confluence switch CS begins 45 substantially simultaneously with the operation of the connector and each has to respond to three digits. If the calling subscriber delays a little in 50 dialling, or if the last three digits of the called number are of high value, the confluence switch may complete its operation first. If this occurs the line relay 201 of the connector is controlled 55 over the talking path through the confluence switch CS to complete the operation of the connector. On the other hand if the connector should complete its operation first, there is no delay in transmitting the busy tone or ring back tone to the calling party, as the repeating circuit 60 at S1 is connected with the control circuit incoming to the line relay 124 by means of a small condenser 141.

There is a considerable advantage in starting the operation of the confluence switch before the 65 dialling is completed as compared to those bypass systems in which the connection is extended clear through to the called line before the operation of the switch or switches which complete the talking path is started. By starting the operation 70 of the confluence switch at the time the operation of the connector is started the talking connection through the confluence switch is usually established by the time the called line is found, or perhaps before, and the delay which 75 would otherwise occur is avoided. At the same

time the holding time of the switches such as S1 and S2 in the setting route is reduced to a minimum.

The foregoing advantages, of course, could not be secured if the connector were by-passed as well as the selectors, which brings up an additional advantage of the present system over those systems which by-pass all the directive switches used in the setting route. It is usually necessary in 5 automatic systems to provide for different types of service among which may be mentioned regular individual line service, selective ringing party line service, code ringing party line service, and trunk service to private branch exchanges. In 10 the ordinary automatic systems these different types of service are furnished by providing different groups of connectors such as individual line connectors, selective ringing or code ringing connectors, and rotary connectors. Thus the 15 connectors in each group are relatively simple 20 switches as each switch only has to give one type of service. In by-pass systems where the final switches are eliminated the advantage of grouping in accordance with service facilities has to be sacrificed because the called lines are extended 25 back to common talking links, and each link has to be of a universal type arranged to give the necessary type of service regardless of the line called. The links, therefore, are excessively complicated. In 30 the present system the connectors are common to the setting and speaking routes, that is, only the selectors are by-passed, and the advantage of grouping the connectors for different types of service is retained. Thus the connector C is one of a group of connectors arranged to provide individual line service. There ordinarily will be 35 other groups of connectors for party line service, and one or more groups of rotary connectors. These different types of connectors are well known and consequently it is not necessary to show them 40 in the drawings.

Since the connectors are of substantially 45 standard types, retaining the functions of battery feed, busy testing, ringing, etc., a confluence switch such as CS has no functions to perform 50 except that of completing the final talking connection between the connector used to find the called line and the trunk circuit to which the calling line is connected, and consequently these confluence switches are of very simple construction. 55

As indicated hereinbefore, the connector C is in general not new, but it has a special feature involving the prevention of clicks at the calling station which is believed to be novel. This feature may be regarded as an improvement on my prior Patent No. 1,376,848, May 3, 1921. The arrangement involves the provision of a battery feed relay 200 which is connected to the talking circuit on the opposite side of the condensers 60 from the back bridge relay 204, and the provision of contacts on the back bridge relay for connecting the incoming trunk conductors 215 and 218 to the battery feed relay in place of the line 65 relay. This circuit not only greatly reduces the click or bang due to reversal of current in the calling line, a result obtained in my prior patent, but it also eliminates the clicks due to the action of the switching through and ring cut-off relays, one or the other of which is present 70 in systems using standard connectors. The elimination of the ring cut-off and switching through clicks is due to the fact that in the present circuit the incoming trunk conductors 215 and 218 are normally entirely separate from the talking 75

circuit in the connector and extend only to the windings of line relay 201. When the back bridge relay operates to disconnect the trunk conductors from the line relay and connect them instead to the battery feed relay 200, it connects these trunk conductors to the talking circuit at the same time.

The invention having been described, what is considered to be new and is desired to be protected by Letters Patent will be set forth in the following claims.

What is claimed is:

1. In a telephone system, means including a finder, a first selector, a second selector, and a connector for extending a call from a calling line to a called line, a confluence switch for bypassing both the first and second selectors, thereby directly connecting the finder and connector, and means for releasing the first and second selectors while the calling and called lines are maintained in talking relation through the finder, the confluence switch and the connector.

2. In a telephone system, a trunk circuit, means for extending a calling line to said trunk circuit, means including selector switches and a connector for selecting a called line, a confluence switch for connecting the connector with said trunk circuit, a sender individual to the trunk circuit for operating said confluence switch to connect the connector switch with the trunk circuit and for maintaining such connection, and means for releasing said selector switches after the connector and trunk circuit have been connected.

3. In a telephone system, a plurality of serially related automatic switches controlled over a calling line to select a called line, a confluence switch for setting up a by-pass connection from the calling line to the final switch, means for starting the operation of the confluence switch concurrently with the final switch, and means for completing the operation of the final switch over the by-pass connection if said connection is established before the called line is selected.

4. In a telephone system, a setting route involving selector switches and a connector switch, a speaking route excluding said selectors but including said connector, and operating means in said connector controllable either over said setting route or said speaking route.

5. In a telephone system, a setting route involving selector switches and a connector switch, a speaking route excluding said selectors but including said connector, means for starting the operation of said connector over said setting route, and circuit arrangements whereby the operation of said connector may be completed over said speaking route.

6. In a telephone system, a setting route involving selector switches and a connector switch, a speaking route excluding said selectors but including said connector, means for starting the operation of said connector over said setting route, means for concurrently starting the establishment of the speaking route, and means for completing the operation of said connector over the speaking route in case the same is established before the connector is fully operated.

7. In a separate setting and speaking route system, a confluence switch for completing the speaking route, a control circuit for said switch included in the setting route, and means for transmitting both direct current impulses and alternating current impulses over said circuit to control the operation of said switch.

8. In a separate setting and speaking route system, a confluence switch for completing the speaking route, a control circuit for said switch included in the setting route, said switch having primary and secondary operating movements, means for sending direct current impulses over said circuit to control said switch in its operating movements, and means for sending alternating current impulses over said circuit to control the changeover in said switch from its primary movement to its secondary movement.

9. In a separate setting and speaking route system, a final connector, a confluence switch for completing the speaking route and individual to said connector, an operating circuit for said confluence switch, and means responsive to the beginning of the operation of said connector for completing said operating circuit.

10. In a separate setting and speaking route system, a connector switch for connecting with a called line, means including a train of selector switches for selecting and operating said connector from a calling line, a confluence switch associated with said connector for connecting the same with the calling line over a talking path excluding said train of switches, means in said connector for testing and ringing the called line, and means in said connector for supplying talking current for both the calling and called lines.

11. In a telephone system, a setting route involving selector switches and a connector, a speaking route involving a confluence switch and said connector, a control circuit included in the setting route over which a calling subscriber transmits impulses to operate said connector, a second control circuit included in said setting route, and a sender operating concurrently with the subscriber's calling device to send impulses over said second control circuit in the same direction as the impulses in said first control circuit and effective to operate said confluence switch.

12. In a telephone system, a setting route including a selector repeater and a connector, means for operating said connector under control of said selector repeater, a speaking route including said connector but excluding said selector repeater, means for starting the establishment of the speaking route while the connector is operating, and means effective if the operation of the connector is completed before the speaking route is established for transmitting tone currents back over the setting route from the connector to the calling subscriber.

13. In a connector switch, talking conductors each including a condenser, a battery feed relay and a back bridge relay bridged across said talking conductors on opposite sides of said condensers, a line relay, incoming trunk conductors normally connected to said line relay and disconnected from said talking conductors, and contacts on said back bridge relay for disconnecting said trunk conductors from said line relay and for connecting them to said battery feed relay.

14. A connecting switch as claimed in claim 13, characterized by the provision of contacts on the battery feed relay for holding the line relay energized after the trunk conductors have been disconnected.

15. A connector switch as claimed in claim 13, in which the battery feed relay and line relay are so connected to the battery that the substitution of the battery feed relay for the line relay causes a reversal of current in the trunk conductors.

16. In a telephone system, a connector switch including operating means, a setting route including selector switches and said operating means, a speaking route including said operating means and excluding said selector switches, said routes being adapted to be completed following the initiation of a call thereover, means for starting the operation of said operating means over said setting route, and means for completing the operation of said operating means over said speaking route.
17. In a separate setting and speaking route
- telephone system, a confluence switch for completing the speaking route, said switch having primary and secondary movements, a control circuit for said switch included in at least one of said routes, means for sending current impulses of one kind over said circuit to control said switch in its operating movements, and means for sending current impulses of a different kind over said circuit to terminate one of said movements and to start the other of said movements. 10

BERNARD D. WILLIS.
